CUT STONE FOR COSTUME JEWELRY

William Wachtenheim, Great Neck, N. Y.

Application February 10, 1958, Serial No. 49,583

Term of patent 7 years

(Cl. D45—1)

Fig. 2.

Fig. 1.

Fig. 3.

Fig. 4.

Fig. 5.

Fig. 6.

Fig. 1 is a top plan view of a cut stone for costume jewelry, showing my new design;

Fig. 2 is a bottom plan view;

Fig. 3 is a side elevational view;

Fig. 4 is a sectional view taken on the line 4—4 of Fig. 1;

Fig. 5 is a front elevational view of Fig. 1; and

Fig. 6 is a sectional view taken on the line 6—6 of Fig. 1.

I claim:

The ornamental design for a cut stone for costume jewelry, substantially as shown.
